SHIRT OR THE LIKE

George London, Brooklyn, N. Y.

Application November 24, 1953, Serial No. 27,766

Term of patent 14 years

(Cl. D3—25)

To all whom it may concern:

Be it known that I, George London, of New York, N. Y., have invented a new, original, and ornamental Design for Shirts or the like, of which the following is a specification, reference being had to the accompanying drawings forming part hereof.

Figure 1 is a front elevational view of the shirt or the like; and

Figure 2 is a back view similar to Fig. 1.

The characteristic feature of my design resides in the arcuate rib-knitted inserts at the sides of the shirt in the arm-pit regions, as shown.

I claim:

The ornamental design for a shirt or the like, substantially as shown and described.
